UNITED STATES PATENT OFFICE.

WILLIAM HANDLEY, OF CAMDEN, NEW JERSEY.

ELASTIC FABRIC.

Application filed June 20, 1923. Serial No. 646,568.

To all whom it may concern:

Be it known that I, WILLIAM HANDLEY, a citizen of the United States, residing in Camden, New Jersey, have invented an Elastic Fabric, of which the following is a specification.

One object of this invention is to provide a novel form of woven fabric particularly adapted for use in the manufacture of garters, corsets, brassières, bandages, etc., where it is desirable that the article shall be practically non-elastic in one direction and relatively elastic in a direction at right angles thereto. Said fabric may be made of silk, cotton or a mixture of these materials and consists of any desired number of parallel tubular stripes whose width, size and direction may be varied between wide limits without departing from my invention.

These objects and other advantageous ends I attain as hereinafter set forth, reference being had to the accompanying drawings, in which,

Fig. 1 is a plan, on an enlarged scale and to some extent diagrammatic, illustrating an elastic fabric made in accordance with my invention;

Fig. 2 is a longitudinal section on the line 2—2 Fig. 1; and,

Figs. 3 and 4 are vertical sections on the line 3—3 and 4—4, Fig. 1.

In the construction of the fabric, I employ a loom using for example six harnesses or any multiple of this number, and of these, the yarns of four harnesses constitute the ground and those of two harnesses constitute the binders. While the weft threads are relatively straight and non-elastic, with but a slight twist, the warp threads are excessively twisted or crinkled. They are thus not only capable of great elongation but by virtue of the natural elasticity of the material of which they are made and of its excessively twisted condition they are highly elastic, so that after an elongating tension is removed, they will return to their original length. The fabric, moreover, is characterized by the fact that when in band

or elongated form it may be drawn out without tending to decrease in width.

The fabric itself consists of two separate weaves connected together by binder threads to form parallel tubular sections, and is of the same construction on its two faces, being longitudinally elastic but laterally inelastic.

In the above drawings, 1—1 represent the weft threads of my fabric which are relatively straight and are made with but a relatively slight twist therein so that they are practically non-elastic. The ground fabric is made up of warp threads 2—2, 3—3 and 4—4 all made of excessively twisted threads so that they tend to assume a crinkled form, may be greatly elongated and are highly elastic. Moreover, said warp threads are preferably so arranged as to give a herring-bone effect to the finished fabric, and further increasing its longitudinal elasticity. As above indicated, the ground warps 2 and 4 are woven about the two sets of weft threads to form two separate weaves which are connected at intervals by the binder warps 3—3, so that the complete fabric is made up of parallel tubular sections which in the case shown extend longitudinally of said fabric and give it a striped appearance. As a result of the use of non-elastic weft threads and highly elastic warp threads, the fabric is practically non-stretchable in a transverse direction, i. e., in the line of the weft threads, but may be greatly elongated in the direction of the warp threads. Owing to the highly twisted condition of the latter, these tend to return to their original length and form after the elongating force has been removed.

I claim:

A fabric consisting of two sets of relatively non-elastic weft threads; two sets of independent excessively twisted warp threads interwoven respectively with the weft threads of said two sets; and binder warps connecting said weft threads of the two sets to form a fabric having tubular stripes.

WILLIAM HANDLEY.
